TILTING BURNER MOUNT

Robert J. Best, Myersville, and Roger W. Tuthill, Mountainside, N.J., assignors to Air Reduction Company, Incorporated, New York, N.Y., a corporation of New York

Filed Sept. 9, 1964, Ser. No. 395,212
10 Claims. (Cl. 266—23)

This invention relates to scarfing apparatus in which jets of oxygen are projected against the heated surface of a slab, billet, or other work piece to remove the surface metal and imperfections therein from the work piece preparatory to rolling or other operations on the work piece.

During a scarfing operation, the burner is held close to the surface that is to be scarfed, and it is common practice to have a shoe or other bearing surface on the burner in position to rub directly on the surface of the work piece. The burner is held with the shoe in contact with the work piece by yielding means that permit the burner to move up and down to follow variations in the contour of the work piece surface and to follow the surface when the work piece is warped or bent.

The scarfing burner is held against movement in the direction of the relative movement of the burner and work piece, and very often an irregular, projecting piece of metal on the work piece will strike a burner and bend or break the burner or the support so that the apparatus cannot be operated again until costly and time-consuming repairs have been made.

Conventional scarfing apparatus often has a plurality of burners located side-by-side across each surface to be scarfed, and these burners or their holders are designed to break away individually from one another if struck by metal projecting from a work piece at a location which catches on a burner.

It is an object of this invention to provide improved supporting means for a scarfing burner, and to hinge the supporting means so that the burner can swing against a yielding force that softens the blow and prevents damage to the apparatus if the burner is struck by a metal projection or other obstruction.

Features of the invention relate to the combination of a spring with specific operating mechanism and to the particular kind of spring used for yieldably holding a scarfing burner in working position; and to provision for damping the spring action to prevent oscillation of the burner along the work piece.

Another object is to provide scarfing apparatus having a support for yieldably holding a burner against movement with respect to a supporting mount and in the direction of movement of the work piece, and with other yielding means for holding the burner and supporting mount assembly in position to maintain the burner adjacent to the surface of a work piece on which the burner is operating.

Other objects, features and advantages of the invention will appear or be pointed out as the description proceeds.

In the drawing, forming a part hereof, in which like reference characters indicate corresponding parts in all the views:

FIGURE 1 is a diagrammatic side elevation of scarf-

2

ing apparatus made in accordance with this invention; and

FIGURE 2 is a fragmentary rearward view of a portion of the apparatus shown in FIGURE 1.

5 A slab or work piece 10, which is to be scarfed, is advanced in the direction indicated by an arrow 12 along a conveyor 14 having rollers 16 which support the work piece 10. There is a space between the rollers 16 at a scarfing station and a scarfing burner 20 is held in a position adjacent to a bottom surface 22 of the work piece 10. This invention will be described in connection with the burner 20 which scarfs the bottom surface 22, but it will be understood that there are other burners for simultaneously scarfing the other sides of the work piece 10; and this invention may be applied to these other burners.

20 The burner 20 directs pre-heating and scarfing jets against the work piece 10 in a direction opposite to the direction of movement of the work piece. The direction of impingement of the jets from the burner 20 against the work piece 10 is indicated by the arrow 24 in FIGURE 1. The scarfing jets are located along a row extending transversely of the work piece 10 so that the entire bottom surface is scarfed in a single operation.

25 The scarfing burner 20 is supported by a mount or mounting frame 30 having a relatively-fixed part 32 secured to structure 34 of the scarfing apparatus. The mounting frame 30 also has a movable part 36 attached to the relatively-fixed part 32 by hinge means 40.

30 The hinge means 40 includes a shaft 42 which serves as a pin for the hinge means. This shaft 42 extends through side portions 44 of the movable part 36 and through a middle portion 46 (FIGURE 2) of the relatively-fixed part 32 of the mounting frame 30. A set screw 48 holds the shaft or pin 42 against axial movement.

35 The burner 20 has a bracket portion 50 which fits over the upper end of the movable part 36 of the mounting frame 30 and the bracket portion 50 of the burner is attached to the movable part 36 of the mounting frame 30 by fastening means, such as screws 52 (FIGURE 1).

40 In the preferred construction, the burner 20 has a shoe 56 that rubs along the bottom surface 22 of the work piece and the bearing surface of the shoe 56 is located behind a plane 58 which extends through the axis of the shaft 42 and at right angles to the bottom surface 22 of the work piece 10. The entire portion of the burner 20, which is adjacent to the bottom surface 22, is located behind (to the left in FIGURE 1) the plane 58 so that, if an irregularity extending from the bottom of the work piece 10 strikes the burner 20 and swings the burner about the axis of the shaft or pin 42, the burner moves away from the work piece instead of jamming against it, as would be the case if the shoe 56 and adjacent portions of the burner were located in front (to the right in FIGURE 1) of the plane 58.

45 Forward-swinging (clockwise) movement of the burner 20 about the hinge shaft or pin 42 is limited by a block 62 secured to the front of the movable part 36 of the mounting frame 30 by fastening means including screws 64. This block 62 extends downward below the shaft 42 and strikes against a surface 66 of the relatively-fixed part 32 of the mounting frame 30 so that the mounting

frame cannot move any further than into a straight up-and-down position when the movable part 36 swings clockwise. There are screws 68 threaded through the block 64 for adjusting the heights of the burner 20 with respect to the mounting frame 30. These screws 68 are locked in adjusted position by jam nuts 70.

Rearward-swinging (counterclockwise) movement of the burner 20 about the shaft or pin 42 is limited by spring means including a multi-leaf spring 74. This spring 74 extends both above and below the level of the shaft or pin 42; and the lower end of the spring 42 is clamped against a back face 76 of the relatively-fixed part 32 of the mounting frame 30, by a block 78. This block 78 is held against the spring 74 by screws 80 which extend through the block 78 and spring 74 and which thread into the relatively-fixed part 32 of the mounting frame 30. A part of the block 78, which extends upward, has a front surface 82 that curves away from the spring 74. This curved surface 82 controls the bending of the spring 74 and has the effect of shortening the free end of the spring 74, and thus increasing the spring rate as the spring bends toward the left in FIGURE 1. A position of the spring 78, when bent back by a substantial distance, and adjacent parts of the mounting frame 30, are shown in dotted lines in FIGURE 1.

Although the part 36 of the mounting frame 30 can be made to bear directly against the front leaf of the spring 74, the preferred construction of the invention has a shim 86 attached to the part 36 of the mounting frame 30 by screws 88, and this shim 86 moves along the surface of the spring 74 as the burner 20 swings counterclockwise in FIGURE 1. The extent of this movement is indicated by a dimension arrow 90 in the drawing.

The leaves of the spring 74 also move on each other as the spring bends, since the leaves are clamped together only at their lower ends by the screws 80. This movement of the shim 86 and movement of the spring leaves on one another creates friction for dampening the operation of the spring and thus prevents the spring from oscillating and causing the burner 20 to oscillate back and forth with resulting variations in the application of the scarifying jets to the work piece.

The structure 34 of the scarifying apparatus holds the mounting frame 30 against movement in the direction in which the work piece travels, but in the preferred construction the structure 34 is movable up and down toward the work piece 10 so as to carry the burner 20 into contact with the work piece for a scarifying operation. The means which hold the burner 20 up against the workpiece are yielding means so that the burner 20 can move up and down to follow the contour of bent slabs, and provision is sometimes made for permitting rocking of the burner to follow the contour of a warped slab. Details of this apparatus for holding the burner against the work piece are not a part of this invention but it is a feature of the invention and the assembly described can be carried by structure 34 which is movable up and down by yielding means for maintaining the burner 20 in contact with the work piece. Although the structure 34 is held against movement in the direction of movement of the work piece 10, and against transverse movement, it can only be described as "relatively-fixed" or "relatively-stationary," because of its up-and-down movement.

FIGURE 1 shows diagrammatically a mechanism for raising and lowering the structure 34. This structure is shown connected to a fixed element 94 by a pivot connection 96; and there is a cylinder-and-piston motor 98 which is supplied with working fluid through piping 102 and 104 to move the structure 34 angularly about the pivot connection 96. Valves 106 are operated to control the supply and exhaust of working fluid in the piping 102 and 104 to control the operation of the cylinder-and-piston motor 98.

The preferred embodiment of the invention has been illustrated and described, but changes and modifications can be made and some features may be used in different

combinations without departing from the invention as defined in the claims.

We claim:

1. A scarifying apparatus comprising a scarifying burner mounting means, a scarifying burner which directs oxygen jets against the work piece in a direction substantially opposite to the movement of the work piece, said burner attached to said mounting means and having a work piece abutting surface, said mounting means including a mounting frame comprising a relatively-fixed part, and a movable part having mounted thereon said scarifying burner, hinge means by which the movable part is attached to the relatively-fixed part of the frame, the hinge means having an axis extending transversely of the direction of movement of a work piece with respect to said burner and positioned in a plane normal to the workpiece surface at the most forward point of contact between the work piece and said abutting surface of said burner or forward thereof, and spring means yieldably resisting the swinging of the movable part in a direction to permit said burner to move for a limited distance with a work piece having an irregular portion that strikes against the burner during a scarifying operation.

2. The scarifying apparatus described in claim 1 characterized by the spring means being oriented to resist rearward movement of the movable part, and an adjustable stop for limiting forward movement of said movable part of the frame by said spring means.

3. The scarifying apparatus described in claim 1 characterized by the spring means including a leaf-spring, a portion of which extends behind the movable part of the mounting frame and another portion of which extends behind the relatively-fixed part of the mounting frame.

4. The scarifying apparatus described in claim 3 characterized by an abutment surface behind the spring and extending behind the portion of the spring that is behind the movable part of the mounting frame and curving away from the spring as the spring extends further from the hinge means.

5. The scarifying apparatus described in claim 4 characterized by the spring being a multi-leaf spring with leaves that slide on one another as the spring flexes, whereby the movement of the leaves on one another damps the spring action to prevent oscillation of a burner supported by the mounting frame.

6. In scarifying apparatus in which a work piece moves with respect to a scarifying burner that directs oxygen jets against the work piece in a direction substantially opposite to the movement of the work piece with respect to the burner, a burner, a supporting frame for the burner, a pivot by which the supporting frame is connected with a relatively stationary part of the apparatus and on which the supporting frame swings rearward in the direction that the work piece is moving to relieve shock on the burner as it is struck by an irregularity of the work piece, spring means for returning the burner to its forward position after the irregularity passes, and a stop for determining the forward position of the support.

7. The scarifying apparatus described in claim 6 characterized by a conveyor along which successive work pieces travel, means holding the relatively stationary part of the apparatus in position to hold the burner in contact with the surface of the work piece to be scarfed, the stop for determining the forward position of the support being on the relatively stationary part of the apparatus.

8. The scarifying apparatus described in claim 7 characterized by the stop for determining the forward position of the support being adjustable to vary the forward position of the burner with respect to the apparatus, and the means for holding the relatively stationary part of the apparatus in position being a yielding means having movement for shifting the burner support toward and from the work piece but having means holding it against shifting in the direction in which the supporting frame swings rearwardly.

9. The scarifying apparatus described in claim 8 charac-

terized by the spring being a leaf-spring and the support having an abutment surface that slides on the leaf-spring as the spring bends, whereby movement of the spring is damped to prevent oscillation of the burner.

10. The scarfing apparatus described in claim 6 characterized by a conveyor along which the work pieces travel, the scarfing burner having a surface thereon which bears against a surface of a work piece on the conveyor during relative movement of the work piece and the burner, said surface of the burner being located rearward of a plane intersecting the axis of the pivot and normal to the work piece surface.
